STRAINING TANK

Frank H. Schwaiger, La Due, Robert C. Gadsby, St. Louis County, and Joseph Schwaiger, Afton, Mo., assignors to Anheuser-Busch, Incorporated, St. Louis, Mo., a corporation of Missouri

Filed Nov. 16, 1959, Ser. No. 853,330
6 Claims. (Cl. 195—135)

This invention relates to an improved straining tank or grain extractor or lauter tub, and more particularly to an improvement in an existing kind of lauter tub presently in widespread use in the brewing industry to remove extract from brewers' grains.

This invention relates to an improvement in existing lauter tubs having agitators therein which increases the efficiency or reduces the draw-off time to about two-thirds of the time previously required. This is important because the lautering step in the brewing process has in the past been one of the slowest and one of the bottlenecks in the production of beer. In other words, in the usual brewing operation today, the capacity of the step which uses lauter tubs or straining tanks largely determines the capacity of the brewery.

In our co-pending applications Serial No. 724,561, filed March 28, 1958, now Patent No. 2,916,421, granted December 8, 1959, and Serial No. 788,689, filed January 23, 1959, now Patent No. 2,936,236, granted May 10, 1960, we disclose a new type of straining tank and method, which completely replaces lauter tubs of earlier designs having agitators therein. The straining tank described in said co-pending application is especially useful in new installations, such as when new breweries are built or when new lauter tubs are required in existing facilities.

The purpose of the present invention is to improve the operation and/or efficiency of existing lauter tubs which are still in good condition and which cannot be economically replaced. At present, the conventional type lauter tub used in the brewing industry is a relatively large and expensive piece of equipment. Its diameter is usually from about 12 feet to 27 feet and it has a heavy and expensive power driven rake or lauter machine which rotates therein to agitate and loosen the grains. This is sometimes referred to as an agitator. Typical devices of this sort are shown in United States Patent Nos. 2,014,945, 2,150,009, 2,262,863, and others.

One of the principal objects of the present invention is to modify and improve existing lauter tubs to materially increase their capacity in the brewing operation or reduce the time required for the straining operation. Another object is to reduce the straining time by as much as one-third by modifying the existing lauter tub in a relatively simple and inexpensive manner. Another object is to provide a lauter tub in which the pull of the wort through the thick grain bed is relatively easy since the grains do not tend to compact as much as in conventional lauter tubs. Another object is to maintain the grain bed in a loose condition so that the grains near the false bottom are relatively loose. Another object is to provide for greatly improved operation with only a minor and relatively inexpensive change in the existing equipment.

Still another object is to provide an additional draw-off level over that heretofore used in conventional lauter tubs in order to improve the efficiency of the operation and maintain excellent quality at the same time.

These and other objects and advantages will become apparent hereinafter.

This invention is embodied in a lauter tub of the existing and conventional type having an agitator therein, said lauter tub having a slotted ring tube inwardly of the vertical lauter tub wall, the top of said tube positioned slight-

2

ly below the top level of the grain bed, said slotted ring tube having draw-off pipes leading to a header for controlling the flow from said slotted ring tube, and a pipe from said header to the grain, said grain also receiving wort in the normal manner through pipes leading from the false bottom through which much of the wort is drawn.

The invention is also embodied in a system for drawing off the first wort from an upper point slightly below the top of the grain bed, continuing the draw-off from said upper point, and thereafter drawing off the wort from both the upper point and through the false bottom in the usual manner, thereby reducing the draw-off time substantially.

This invention also consists in the parts and in the arrangements and combination of parts hereinafter described and claimed. In the accompanying drawings which form part of the specification and wherein like numerals and symbols refer to like parts wherever they occur:

FIG. 1 is a side elevational view, partly in section, illustrating a lauter tank embodying the present invention.

FIG. 2 is a horizontal cross-sectional view taken along the line 2—2 of FIG. 1.

FIG. 3 is a bottom plan view of the draw-off tubes and control valves which are located beneath the lauter tank.

FIG. 4 is an enlarged vertical cross-sectional view taken along the line 4—4 in FIG. 2 showing the slotted ring tube.

FIG. 5 is an enlarged fragmentary top plan view of a portion of said slotted ring tube.

FIG. 6 is an enlarged view of one of the removable sections of said slotted ring tube, and

FIG. 7 is a front elevational view of the controls for controlling the pull and the draw-off of the wort from the false bottom and from the slotted ring tube.

Referring now to the drawings in detail, which show a lauter tub about 27 feet in diameter, it will be seen that the embodiment of the invention which has been illustrated is provided in a straining tank or lauter tub 1 having a cover member 2 and a bottom member 3 with a cylindrical wall 4 therebetween. The cover member 2 is provided with a vent stack 5 and openings or manholes 6. The cylindrical wall 4 is insulated as indicated by the reference numeral 7. The bottom member 3 is suitably supported, as at 8, and is provided with a plurality of spaced draw-off connections 9 which are connected by suitable piping 10.

The straining tank 1 is provided with a rotating mechanism or agitator 11 which subjects the batch of grain, not shown, in the tank to a momentary separation. The lauter rotating mechanism 11 comprises a vertical shaft 12 which extends upwardly from the bottom member 3 along the central axis of the straining tank 1. The shaft 12 is operatively connected to a hydraulic cylinder 13 which is operated by a rotating shaft 14 extending upwardly from a gear unit 15 which is actuated either by a low-speed drive shaft 16 or a high-speed drive shaft 17 driven by prime movers not shown. The low-speed prime mover preferably causes the rotating shaft 14 to rotate about 0.25 r.p.m., whereas the variable speed larger prime mover causes the shaft 14 to rotate between 4 to 10 r.p.m.

Two agitating arms 18 extend radially outwardly from said vertical shaft 12 and each arm 18 is provided with a plurality of rotatable or adjustable spaced knife members 19. These spaced knife members 19 are adjusted by suitable control means 20 mounted on said arms 18. A substantially horizontal inner or false bottom 21 is provided below the bottom edges of the knife members 19.

and above the bottom member 3. The bottom member 3 is shown with valleys or sloping portions to direct the flow of wort, but the bottom may be of any suitable design. The inner bottom 21 is provided with openings or slots 22 over its entire surface.

Suitable grain discharge slide gates 23 are provided in the bottom member 3 for removing the grain from the lauter tub 1. The inner or false bottom 21 is preferably formed from a plurality of perforated false bottom sections 24, each supported by upstanding pedestals and locking devices which maintain the inner bottom 21 and bottom member 3 in spaced relation. The false bottom 21 is also provided with a grain discharge slide gate which registers with the slide gate 23. A suitable grain inlet 26 is positioned in the wall 4 of the tank.

The straining tank 1 is provided with a sparge line 27 which extends vertically upwardly along the cylindrical wall 4 and enters the lauter tank 1 through an opening 28 in the cover member 2. The sparge line 27 feeds two circular headers 29 and 30 each having a plurality of holes or openings 31 positioned in the upper portion of the lauter tank 1 for washing the rotating mechanism 11 as well as the inside surface of the lauter tank 1 and includes spraying and supplying water to grain bed for purpose of extracting wort.

The draw-off connections 9 have suitable draw-off tubes 10 extending therefrom which lead to connections 32 which in turn lead to control valves 33. A separate control valve 33 is provided for each of the draw-off connections 32 and these valves are preferably positioned close together, as shown in FIG. 3.

By use of the three valves 33, the flow of the wort from the evenly spaced draw-off connections 9 can be controlled. These valves 33 can be regulated so that each draw-off connection 9 draws off the same amount of wort. In the well known manner, the valves 33 can be controlled to properly deliver the wort from each pipe 10 and 32 through the line 34 to the grant 35. The line 34 is also provided with a slide valve 36 and suitable pipes for cold water and for sparge water.

The structure described in detail in the last several paragraphs has been known in the prior art and has given good results for many years. Our improvement which greatly improves the operation of the lautering step comprises adding an additional draw-off means or slotted ring tube 40 at a critical position within the lauter tub 1. We have found that the draw-off time can be reduced from 140 minutes to 92 minutes in a typical lauter tub having a diameter of about 27 feet simply by using the slotted ring tube 40 and piping hereinafter described.

In practice, we have found that the slotted ring tube 40 should preferably be of the cross-section shown in FIG. 4. This shape is generally pointed at the top 41 and has two sides 42 and 43 which curve gradually into a curved bottom portion 44. This shape tends to prevent grains from accumulating on the tube 40. The vertical height of the ring tube 40 in a lauter tub about 27 feet in diameter from the point 41 to the lowermost portion of the curved bottom 44 is approximately 5 inches and its greatest horizontal width between the side wall 43 and the remote joining of the side wall 42 and curved bottom 44 is about 5 inches. The gradual curves and absence of sharp corners facilitate cleaning. The ring tube 40 contains a plurality of openings or slots 45 which are slightly staggered. These slots are approximately $\frac{1}{2}$ inch long and 0.025 inch wide although holes of the same width may be used if desired. The 0.025 inch dimension is critical for grains of the size normally used in a typical brewing operation and should not be increased even as much as 0.002 inch since such will allow undesired particles from the grains or husks to get into the wort draw-off system thereby causing the wort to be cloudy or otherwise unsatisfactory. The preferred distance be-

tween the slots is about $\frac{1}{8}$ inch, although this distance can be varied within limits for maximum efficiency.

The precise position of the ring tube 40 in the lauter tub 1 is critical for the most efficient operation. We have found that the most important distance is the distance which the point 41 of the ring tube 40 is positioned below the top level of the grains in normal operation. This distance should preferably be about 2 inches although it can be varied between about one and three inches. Any further deviation outside of the one to three inches preferred range results in gradual but marked decreased efficiency as the distance varies from the preferred 2 inches. However, there will be increased efficiency at almost any vertical distance which the ring tube 40 is placed in the upper half of the grain bed, as compared to a lauter tub having no ring tube 40 therein. We prefer to attach the ring tube 40 by suitable means, preferably welded brackets directly to the cylindrical wall 4 so that there is a space S of about three inches between the cylindrical wall 4 and the closest portion of the generally vertical side wall 43 of the ring tube 40. This distance can be varied slightly within limits, but should not be increased so greatly as to interfere with the knife members 19 which are required for suitable separation and agitation of the grain bed in a lauter tub of the conventional type. With this preferred distance, only the outer knife blade 19 needs to be removed from the arm 18 to provide the necessary outer annular space 47 for the ring tube 40. With new lauter tubs of this design, the arm 18 can initially be made shorter so as to provide the necessary space 47 between the outermost knife blade 19 and the cylindrical wall 4.

Since cleanliness is so important to proper brewing operations, several removable sections 48 are provided in the slotted ring tube 40. These sections 48 have suitable fastening means 49 and 50 thereon for engaging and disengaging the ends of the permanently mounted sections 51 of the ring tube 40. Each removable section 48 can be cleaned separately and each permanent section 51 can be cleaned by inserting a hose or a cleaning rod through its open ends which are exposed when a removable section 48 is disengaged. The ring tube 40 is generally concentric with the cylindrical wall 4 and substantially horizontal.

The ring tube 40 has several draw-off connections 52 spaced equally apart, each provided with a shut-off valve 52a. The connections 52 lead to draw-off tubes 53 and pipes 54 having control valves 55 therein. Each draw-off tube 53 is preferably 2 inches in diameter and leads to a 3 inch diameter connecting pipe 54 which is connected to a larger pipe 56 which leads to an upstanding header 57 whose upper portion extends at least to the level of the point M. The valves 55 connected to the tubes 53 and pipes 54, which have hydrometers connected therein, are necessary for uniformity of extract. As shown, the four draw-off connections 52 are spaced ninety degrees apart and the tubes 53 on the left, as shown in FIG. 3, are the same length as their opposite tubes 53 on the right. That is, the two tubes 53 which lead to a common junction with each of the two pipes 54 should preferably be of equal length to give proper flow and pull.

The header 57 has a sight tube 58 thereon for determining the head or liquid level within the header 57. A pipe 59 with a control valve 60 therein connects the header 57 with the grant 35. This piping is best shown in FIGS. 3 and 7, the former of which shows a bottom elevational view of the piping leading to the grant.

The header 57 is preferably about 6 inches in diameter and about 12 feet tall, with a drain 61 and valve 62 therefore at the bottom. The header 57 is important to the operation of the ring tube 40. It acts as a control for the amount of flow, that is, controls the suction. It avoids excessive pull and too much draw-off from the ring tube 40. And it keeps the mash surrounding the

ring tube in a loose condition. In practice, the liquid level in the header is maintained slightly higher than the level of the ring tube 40 and the high point 63 of the gooseneck 64 connected with the false bottom 21 is positioned slightly above the level of said false bottom 21. The valve 36 can be closed or opened to allow wort to pass through the gooseneck 64 or the pipe 65 which leads into the grant 35 near the bottom thereof.

A sight tube 66 is provided to indicate the height of the liquid in the tub 1, and another sight tube 67 is provided to indicate the pull through the false bottom 21 just as the sight tube 58 indicates the pull through the ring tube 40. The sight tubes 58, 66, and 67 are preferably positioned close together so they can be read with ease. Each is provided with a drain at the bottom with a valve therein. The sight tube 58 should also have a sight tube, not shown, which indicates the level of the liquid in the tub, associated with it for comparison purposes, just as the sight tube 67 has the tube 66. If desired, this sight tube may be a take off from the tube 66. Such a tube can be eliminated, however, if the sight tubes 58, 66, and 67 are closely positioned.

The operation of a lauter tub embodying the present invention is the same as the operation of a conventional lauter tub without the slotted ring tube 40 as are its piping, normal maintenance, loading and unloading of the grains, basic cleaning, and other matters except as follows. With all parts absolutely clean and controls in their proper position, the lauter tub is filled with mash or brewers' grains with sufficient water. This is pumped in through the inlet until the top level of said mixture reaches about to the point M in the tub. The inlet 26 is then closed. This requires about 10 minutes. After a proper period during the clarification and rest, hereinafter described, the grains settle to a level at the point G which is just below the arm 18 and about 2 inches above the top 41 of the ring tube 40.

The valves 33 and 36 are then opened to clarify the wort in the regular manner through the false bottom 21. This requires about 10 minutes, but after the first 7 minutes the valves 55 and 60 from the ring tube 40 are opened so that clarification also takes place through the ring tube 40. Thus, clarification of the wort requires about 10 minutes, the first 7 minutes of which results from clarification only through the false bottom 21 and the last 3 minutes of which takes place through the false bottom 21 and through the ring tube 40. After the wort indicates that clarification has started, the grains are allowed to rest for a proper time, usually 20 minutes, during which time the agitator rotates slowly to keep the grains separated.

The false bottom 21 and the ring tube 40 are then tapped at the same time by opening the valves 36 and 60 to draw-off the first wort. The first wort continues to be drawn off for a short time, usually 30-40 minutes, and sparging thereafter begins in the regular way after the valve 36 has been closed to direct the wort through the gooseneck 64. Sparging is accomplished by opening a valve to allow water to enter the grain bed through the pipes 29 and 30 as wort is being extracted through the pipes 32 and 54. Drawing off of the wort continues through the false bottom 21 and the ring tube 40 until such time as the extract at the ring tube level is reduced to about 2.0 Balling, after which the valve 60 is closed to shut off the flow from the ring tube 40. The valves 33 and 55 are used to regulate the flow. The draw-off continues through the false bottom 21 until the wort is reduced to about 1.0 to 2.0 Balling at which time the draw-off is discontinued. The grain traps 23 and 25 are then opened and all of the grains are removed.

With the grain traps 24 and 25 still open most of the time, the tank is flushed and cleaned. This is accomplished by opening the water valves and allowing water to surge through the circular headers 29 and 30. After a limited number of brews, the tub is completely hosed and cleaned making certain that the walls 4, the ring

75 tube 40, the false bottom 21, and all other portions are clean. This is done in the usual manner.

In practice, we have found that the ring tube 40 can be used to draw-off the first wort completely and can be used for extraction during the sparging period for about one-third of the time required for sparging. This decreases the time required for the entire step by as much as one-third. In actual production with a 27 foot diameter tub wherein the mash has a depth of about 32 to 36 inches and the grain bed or bed of solids is about 12 to 14 inches high, we have been able to reduce the total time of the lautering step from about 140 minutes to 92 minutes. It is believed that this great increase in efficiency results from the fact that the pull through the false bottom is lessened so that the grains at the false bottom 21 are maintained in a loose condition and are less tight and the entire grain bed remains relatively loose, as compared to a conventional lauter tub without the ring tube and its piping. This relatively loose condition remains even after the ring tube is shut off.

In practice, we have taken as much as half of the wort from the ring tube 40, the remaining half coming through the false bottom 21. This reduces the amount of wort or liquid moving downwardly through the entire grain bed. This is important since a so-called "upper dough" or coagulated protein forms on the top of the grain bed in normal operation. The upper dough floats readily and generally is pulled into the grain bed toward the false bottom by the action of the agitator blades where it gathers and further tends to restrict the flow. Our ring tube 40 reduces the movement of the upper dough due to a lesser volume of wort being drawn through the false bottom. Even after the ring tube is shut off in our operation, the general condition of the grain bed for the remaining portion of the step remains in a relatively loose condition.

In a conventional tub, the great pull of the wort through the grain bed tends to compact the grains and slows straining with the result that the operator then moves the controls to increase the pull to obtain wort at a faster rate which in turn tends to compact the grains more tightly. The ring tube 40 serves as an additional draw-off means located at a critical point so as to receive wort with a high Balling and to serve as a relief against compacting of the grains. If the operator wishes to draw-off wort as quickly as possible, he may control the flow through the ring tube 40 as well as the false bottom 21 thereby not increasing the pull through the false bottom 21 with the resulting endless cycle of compacting the grains, increasing the pull, which in turn compacts the grains further.

It will be seen that the invention comprises a lauter tub having a slotted ring tube critically positioned within the tank in a manner which does not interfere with the preferred agitation of the grain bed and through which a portion of the wort can be drawn to reduce the pull through the false bottom thereby tending to improve the loose characteristic of the grain bed and reduce the total time for extraction.

The distances referred to herein are preferable for maximum efficiency but can be varied within limits with lauter tubs of different sizes. Efficiency drops and moves toward the normal efficiency of a conventional tub as one moves away from the preferred distances used for a particular size of conventional lauter tub.

This invention is intended to cover all changes and modifications of the example of the invention herein chosen for purposes of the disclosure, which do not constitute departures from the spirit and scope of the invention.

What we claim is:

1. A straining tank having a bottom, a cover positioned above said bottom with a tubular wall therebetween, said tank having an inlet therein for receiving granular material which forms a bed of solids and an

outlet in the bottom thereof for removing said material, means for directing water into said tank, said tank having an agitator therein which moves through said granular material, said bottom having a slotted false bottom positioned thereabove through which wort may drain, a slotted ring tube positioned above said false bottom and below the top level of said bed of solids and being positioned substantially in the upper half thereof and inwardly of said tubular wall, and draw-off pipes from said ring tube and said bottom below said false bottom for controlling the flow of wort from said tank.

2. A straining tank having a bottom, a cover positioned above said bottom with a tubular wall therebetween, said tank having an inlet therein for receiving granular material which forms a bed of solids and an outlet in the bottom thereof for removing said material, means for directing water into said tank, said tank having an agitator therein which moves through said granular material, said bottom having a slotted false bottom positioned thereabove through which wort may drain, a slotted ring tube positioned above said false bottom and slightly below the top level of said bed of solids and being positioned substantially in the upper half thereof, said ring tube being positioned adjacent to and slightly inwardly of said tubular wall and supported thereby, and draw-off pipes from said ring tube and said bottom below said false bottom with valves therein for controlling the flow of wort from said tank.

3. A straining tank comprising an upright tubular body portion with a bottom and false bottom adjacent to the bottom portion thereof and a cover adjacent to the top portion thereof, said tank having an agitator rotatably mounted therein at a level between said false bottom and said cover, a slotted ring tube positioned between said false bottom and said cover, said slotted ring tube positioned inwardly of and adjacent to said tubular body portion and in circumscribing relation to said agitator, an inlet and an outlet in said tank for receiving and removing granular material, an inlet for directing water into said tank, and draw-off pipes from said bottom below said false bottom and ring tube for drawing-off wort from said tank.

4. A straining tank comprising an upright cylindrical body portion with a bottom and slotted false bottom adjacent to the bottom portion thereof and a cover adjacent to the top portion thereof, said tank having an agitator rotatably mounted therein at a level between said false bottom and said cover adjacent to said false bottom, a slotted ring tube positioned between said false bottom and said cover, said slotted ring tube secured to said tubular body portion in circumscribing relation to said agitator, an inlet and an outlet in said tank for receiving and removing granular material, an inlet for directing water into said tank, said last mentioned inlet being positioned higher than said slotted ring tube, draw-off pipes from said bottom below said false bottom and ring tube for drawing-off wort from said tank, said draw-off pipes from said ring tube connected to a vertical header with a control valve connected therewith for regulating the flow from said ring tube.

5. A straining tank comprising an upright cylindrical wall having a bottom and a false bottom adjacent to the bottom portion thereof and a cover adjacent to the top portion thereof, said tank having an inlet therein for receiving granular material which forms a bed of solids and an outlet in the bottom thereof for removing said grains, an inlet for directing water into said tank, said tank having an agitator therein which moves through said grains, said agitator comprising a laterally extending arm

with depending blades thereon, said arm positioned above the normal top level of said grains and said blades extending into said grains below the top level thereof, said false bottom having slots therein through which wort may drain, a slotted ring tube positioned in said tank below the top level of said bed of solids and being positioned substantially in the upper half thereof, said ring tube positioned inwardly of said cylindrical wall and circumferentially outwardly from said blades, draw-off pipes from said bottom below said false bottom with valves therein for drawing-off and controlling the flow of wort through said false bottom, draw-off pipes from said ring tube with valves therein for drawing-off and controlling the flow of wort from said ring tube, said latter mentioned draw-off pipes connected to an upstanding header having a control valve connected therewith for regulating the flow through said ring tube, said header having a height at least as high as the level to which the incoming granular material and water are filled initially in the tank.

6. A straining tank comprising an upright cylindrical wall having a bottom and a false bottom adjacent to the bottom portion thereof and a cover adjacent to the top portion thereof, said tank having an inlet therein for receiving granular material which forms a bed of solids and an outlet in the bottom thereof for removing said material, an inlet for directing water into said tank, said tank having an agitator therein which moves through said grains, said agitator comprising a laterally extending arm with depending blades thereon, said arm positioned above the normal top level of said grains and said blades extending into said grains below the top level thereof, said false bottom having slots therein through which wort may drain, a slotted ring tube positioned in said tank below the top level of said bed of solids and being positioned substantially in the upper half thereof, said ring tube secured to said cylindrical wall circumferentially outwardly from said blades, said ring tube positioned below the level of said inlet for directing water into said tank, and draw-off pipes from said bottom below said false bottom with valves therein for drawing-off and controlling the flow of wort through said false bottom, draw-off pipes from said ring tube with valves therein for drawing-off and controlling the flow of wort from said ring tube, said latter mentioned draw-off pipes connected to an upstanding header having a control valve connected therewith for regulating the flow through said ring tube, said header having a height at least as high as the level to which the incoming granular material and water are filled initially in the tank.
